UNITED STATES PATENT OFFICE

BURT S. MINOR, OF SAN PEDRO, CALIFORNIA

HOISTING CLEVIS

Application filed December 1, 1928. Serial No. 323,184.

This invention relates to a hoisting clevis of the well-known "Wigle" type for use in connection with the drilling of oil wells.

The "Wigle" hook as shown in the re-issued U. S. Patent No. 14,258, issued January 23, 1917, has been adopted as standard equipment for a long term of years, and moreover has generally proven entirely satisfactory with the exception that open mouthed hooks are subjected to excessive strains when raising or lowering long strings of casing and tubing in wells, such undue strains oftentimes causing a hook failure. Further if the safety latch for the hook is not closed the load frequently becomes disengaged therefrom causing serious accidents, and lastly the single spring necessitated by the "Wigle" structure has proven inadequate for supporting the immense loads carried by the hook.

In the present invention all the above recited disadvantages are largely overcome, the hook in the Wigle construction being replaced by a closed yoke for engaging the load and thus preventing an accidental disengagement therefrom. Further as provision is made for employing a plurality of springs of sufficient strength to carry large loads all danger of mutilation of the tubing threads when screwing or unscrewing casing is eliminated.

It is therefore a chief object of the invention to provide a hoisting clevis construction that will eliminate all danger of accidental disengagement of the load carried thereby.

A further object is to provide a device having adequate resilient support for the load carried thereby and thus eliminate the strain and wear on the casing threads when connecting and disconnecting the casing strings.

In the drawings wherein a single embodiment of the invention is shown by way of illustration;

Fig. 1, is a front elevation of the hoisting clevis with parts broken away to more clearly disclose the construction.

Fig. 2, is a side elevation of the same.

In the drawings, 5 designates the hoisting clevis as a whole that preferably consists of

a downwardly extending shank member 6, its upper end being bifurcated and pivotally engaging the lower transverse pin 7 of a travelling sheave block 8 of the usual well known form. Loosely mounted on the shank member is a pair of cross bars 9 and 10, bar 9 resting on the upper part 11 of an anti-friction bearing 12, whose lower part 13 in turn is carried by the flange of a cap nut 14 secured to the threaded end of the shank member. The outer end of both bars are provided with bores through which pass the arms 15, 16, of a yoke 17, the head of the yoke extending below the cap nut in order that it may be freely engaged by the upper arms or bails of a casing elevator (not shown).

Mounted on the arms of the yoke and between the bars are coil compression springs 18, 19, that are intended to resiliently support the load, such as a string of casing, when the same is attached to the yoke, the spring function being exactly the same as in the "Wigle" construction.

Loosely mounted on the shank member 6 and resting on the upper face of cross bar 9 is a sleeve 20 designed to resiliently support the yoke of the clevis when the casing attached thereto is pulled. The upper cross bar 10 bears against an annular abutment 21 formed on the shank member when the clevis is in its normal position, said abutment preventing a further upward movement of the cross bar by the springs, and permitting an easy removal of the nuts from the yoke arms when it becomes necessary to disconnect the parts of the clevis to remove or replace the links of an elevator used in a hoisting operation.

In using the hoisting clevis for pulling well casing the yoke member 17 is first removed from the cross bars by disengaging the nuts therefrom. The elevator links (not shown) are then mounted on the yoke member 17 which is then replaced in its normal position. As the casing string is lifted its weight will cause the springs 18 and 19 to be compressed and the upper cross bar 10 to rest upon the sleeve 20 which sustains the weight of the casing. As a coupling is un-

screwed from the end of a stand of casing the compression springs lift the stand to relieve the threads of the weight of the stand, and as there are two compression springs 5 surrounding the arms of the yoke it will be apparent that they will have sufficient strength to accomplish same.

The springs are designed to exert an expansive force somewhat greater than the 10 weight of a stand. The roller bearings permits the yoke and the casing to be rotated and allow any turning with a minimum of resistance.

15 In actual practice as in the "Wigle" construction a stand of casing weighs considerably over one thousand pounds, and the springs will support a load considerably in excess of said weight, thus when the springs are compressed so that the yoke 10 rests 20 upon the sleeve 20 there is a force of one thousand pounds which lifts the weight of the stand from the coupling threads, and an excess of more than two hundred pounds tending to raise the stand as the coupling 25 is unscrewed.

From the above it will be obvious that by increasing the resilient lifting power over the single spring construction of "Wigle" a much greater load can be lifted than by such 30 construction. Further as the elevator links hang vertically from the yoke member the weight of the casing on the clevis will be equally distributed. Also as the arms of the yoke member are secured to the upper 35 cross bar of the clevis all danger of a yoke failure is obviated.

I claim:

1. A hoisting clevis comprising a support 40 pivotally secured at its upper end, an anti-friction bearing on the lower end of said support, a cross bar carried by said bearing having apertures formed therein, a yoke member passing through the apertures in the cross bar, a second cross bar on said 45 support, the end of the yoke arms detachably engaging said second cross bar, a pair of coiled springs surrounding the yoke arms between the cross bars, and a support to relieve the load on the coiled springs and to 50 limit the downward movement of the yoke when a load is imposed thereon, the yoke being free to rotate in any position.

2. A hoisting clevis comprising a shank member adapted for pivotal suspension, an 55 anti-friction bearing carried by the free end of said shank member, a cross bar disposed on said shank member and engaging said bearing, a second cross bar disposed on said shank member above said first named bar 60 and movable thereon, a yoke member, the arms of said yoke member passing through apertures formed in said cross bars and detachably secured to said second named bar, a coiled compression spring surrounding 65 each of the arms of the yoke member be-

tween the cross bars, means formed on said shank member to limit the upward movement of said second named cross bar, and a sleeve surrounding said shank member and engaging the first named cross bar to limit the downward movement of the yoke member and to relieve the load on the springs when the latter has contracted a predetermined amount.

3. A hoisting clevis comprising a shank 75 member for pivotal attachment, an anti-friction bearing carried by the free end of said shank member, a cross bar carried by said bearing member, a second cross bar mounted 80 on the shank member above the first cross bar, an annular abutment formed on the shank member for limiting the upward movement of the second cross bar, a yoke member detachably secured to the second named cross bar, the arms of the yoke passing 85 through the apertures in the first named cross bar, coiled springs surrounding the arms of the yoke member and bearing against the oppositely disposed faces of the cross bars to hold the yoke in a contracted 90 position, and a support surrounding the shank member and engaging the first named cross bar adapted to limit the downward movement of said yoke and to relieve the load on the resilient means when the latter has contracted a predetermined amount.

In testimony whereof I affix my signature.
